UNITED STATES PATENT OFFICE.

LAZARD KAHN, OF HAMILTON, OHIO.

DESIGN FOR AN ASH-BOX.

SPECIFICATION forming part of Design No. 27,110, dated May 25, 1897.

Application filed April 10, 1897. Serial No. 631,636. Term of patent 14 years.

To all whom it may concern:

Be it known that I, LAZARD KAHN, a citizen of the United States, residing at Hamilton, Butler county, Ohio, have invented and produced a new and original Design for Ash-Boxes, of which the following is a specification, reference being had to the accompanying drawing, which is a perspective view thereof.

The leading feature of my design consists in a box open at its top and having a narrowed outwardly-projecting nozzle open at its front.

A is the box, open at its top, and B is the narrowed outwardly-projecting nozzle, open at its front and closed at its top.

What I claim is—

The design for an ash-box, substantially as shown and described.

LAZARD KAHN.
